CLAIM

The ornamental design for an vehicle front fascia, as shown and described.

DESCRIPTION

FIG. 1 is a perspective view taken from a front, left side of a vehicle front fascia according to our design;

FIG. 2 is a front elevation view thereof;

FIG. 3 is a left side elevation view thereof;

FIG. 4 is a right side elevation view thereof;

FIG. 5 is a top plan view thereof; and,

FIG. 6 is a bottom plan view thereof.

The broken line showing of vehicle front fascia is for the purpose of illustrating portions of the article and forms no part of the claimed design.
